ELIE W. LABOMBARDE, OF NASHUA, NEW HAMPSHIRE.

METHOD AND MACHINE FOR GLOSS COATING PAPER.

Application filed March 2, 1922, Serial No. 540,604. Renewed January 16, 1928.

This invention relates to the production of coated paper in the form of a web, sheets, or cut blanks, especially the latter, and the invention has particular reference to the 5 production of such paper having one or both surfaces presenting a moisture-proof face having a high gloss without having the coating permeating the texture of the paper to any such extent as to show discolorations 10 or spots.

Heretofore the most commonly practiced method of producing moisture-proof paper, either in web form or when cut into sheets or blanks, has involved the immersion of 15 the paper in melted paraffine which will be hereinafter inclusively referred to by the generic term "wax". Such immersion, even when effected at the highest practical speed, has one or both of two objectionable results, 20 viz: it causes the paper to absorb more wax than is necessary to render it moisture proof even when high grade paper is being treated, thereby wasting wax; and it causes the paper to exhibit shady areas or spots 25 where the wax is absorbed more deeply than elsewhere. This latter defect exists more prominently when the paper or board stock is of a cheap or low grade kind sometimes used for cartons. That is, the cartons look 30 discolored because the material is not uniform as to porosity and the wax enters deeper into the paper where it is most porous.

A further objectionable result of the immersion method is that when the usual tapes or string belts are used to carry the blanks through melted wax, the said carriers leave darker marks or stripes where they contacted with the paper. This is because said 0 carriers are necessarily quite heavily coated 5 with wax since they travel continuously into and through and return out of, the hot wax. They carry the blanks down into and lift them out of the hot wax and are therefore 5 in contact with the blanks for a longer period than the time of immersion and consequently the wax has a longer time to soak in, along the lines of the carriers, than it has on those portions of the blanks between the carriers.

In accordance with my invention I do not immerse or dip the paper (hereinafter inclusively referred to as blanks), but flood it with an intermediate or uncontrolled quantity of hot wax while travelling, remove excess wax, and immediately subject

all areas equally to a chilling action, preferably and conveniently a bath of cold water. By the term "flooding" as used herein, I mean that the blanks are directly deluged with such quantity of the wax that some of it overflows prior to the removal of the excess or surplus wax. The flooding operation on any blank, in practice, lasts only about one-third of a second due to the speed of travel of the blanks and therefore the wax 60 has no time to gain access to the texture of the paper or board stock below the surface thereof. It remains entirely on the surfaces in the form of very thin films which are quickly congealed by the action of the cold 65 water so as to present a high finish or gloss. 70

One of the objects of the present invention is to provide blanks for conversion into paper boxes, which blanks are so waterproofed that the boxes will need no waxed paper 75 coverings, or other wrapping, to keep the contents of the boxes dry or to exhibit printed matter or ornamental designs. In other words, the boxes themselves carry the printed matter and also present glossy 80 surfaces.

Another object is to provide blanks which, although carrying a very small amount of wax, are reliably moisture-proof.

Another object is to provide moisture- 85 proof blanks having a uniform surface appearance, without dark areas.

With these and other objects in view, my invention consists in the method and the machine or apparatus substantially as herein- 90 after described and claimed. Incidental thereto, my invention also consists in the improved blank substantially as claimed hereinafter.

Of the accompanying drawings:

Figure 1 is a plan view of my improved machine in one of its embodiments.

Figure 2 represents a section on line 2-2 of Figure 1.

Figure 3 represents a section of one of the 100 rolls on a larger scale than in Figure 2. Figures 4 and 5 are perspective views showing the opposite surfaces of a blank treated by the machine.

At one end of a suitable frame 12 is a 105 table 13 for blanks to be treated. The table is wide (Fig. 1) so that it may support a plurality of piles of blanks side by side, or a single pile of wide large blanks. The table is pivotally supported on a rod 14 to 110

enable it to be adjusted to the desired degree of inclination and held so by a strut or rod 16 passing through a clamp sleeve mounted upon one of several tie rods 18. The blanks 5 from the table pass successively over leaders 19 as they are drawn from the bottom of the pile or piles by feed wheels 20 carried by shaft 21. Below each feed wheel is a small roll 22 carried by an elbow lever 23 10 mounted on the rod 14 and having a spring 24 connected to it. As this feed mechanism is not claimed herein, further description thereof will be unnecessary.

The blanks are fed toward rolls above, 15 and extending substantially the full width of, a pan 25 in which wax is kept melted by steam or by water in a chamber 26. When water is used in the chamber 26 it may be kept hot by any suitable means such as gas burners one of which is indicated at 27 (Fig. 2). The cold water tank where the wax on the blanks is congealed is indicated at 28.

Above the wax basin 25 and mounted in 25 suitable bearings supported by the frame, are the long rolls above referred to. They are driven in the direction of the indication arrows by suitable gears and chain connections not necessary to describe in detail. 30 Three pairs of the rolls are illustrated, but there may be a different number. The lower rolls 29 of the first two pairs between which the blanks pass, dip into the hot wax in the basin 25 and elevate wax therefrom 35 while the upper rolls 30 of said two pairs receive hot wax from overhead pipes presently described. The lower roll 31 of the third pair also dips in the wax basin and the upper cooperating roll 32 of that pair 40 also receives hot wax delivered from above. The said roll 32 is yieldingly mounted in the upper arms of elbow levers 33 having their fulcrums in alinement with the axis of roll 31, the other ends 34 of the arms or levers 45 being slotted to receive screws whereby the elbow levers may be adjusted to hold the roll 32 swung more or less toward the water tank 28 as may be necessitated by the size or character of the blanks to be treated. 50 The reason for this will be explained hereinafter.

Above the several pairs of rolls is a system of perforated piping 35 communicating through a pipe 36 (Fig. 1) with a pump 37 55 in a wax reservoir 38, the shaft 39 of the pump extending through the wall of the reservoir and having a pulley which is connected by a belt 40 with a pulley 41 on the main or other shaft 42 of the machine. By 60 any suitable connections and constant level device the level of melted wax in the basin 25 is kept at the proper height to enable the rolls 29 and 31 to take up an ample quantity of wax, while the pump 37 maintains a circulation 65 of wax from basin 25 (through a

suitable opening) and from the reservoir into the pipe system to keep the rolls 30 and 32 flooded with hot wax. The wax from the pipes heats the upper rolls and keeps them hot. The pump, by its flooding action, 70 supplies the upper rolls with a quantity of hot wax which immediately passes freely over them onto the blanks in quantity exceeding what the passing blanks will take and consequently ensures the preservation 75 of the rolls at the proper temperature without requiring other means for heating the rolls.

It is to be understood that the rolls of the pairs are so adjusted relatively as to 80 move the blanks along without subjecting them to any such pressure as would force wax below the surfaces of the blanks. This is true although the pair 31, 32 are herein-after referred to as squeeze rolls. Said 85 rolls 31, 32, are so set relatively to each other as to remove surplus wax from the blanks after they have been flooded, so that said surplus will drop back into the basin 25.

The speed at which the blanks travel is such that they are quite forcibly thrown or ejected by the rolls 31, 32, edgewise down into cold water which nearly fills the tank 28, and they are directed by said rolls under and adjacent to a large roll 43 which is partially immersed in the water and is driven, as hereinabove described, at a peripheral speed to agitate the water where the blanks enter it. The roll 43 is supported by arms 44 pivoted at 45 to brackets 46 mounted on the side walls of the water tank, and may be adjusted by any suitable means. By adjusting the arms or levers 33 which support the roll 32, the latter may be set to cause 100 the blanks to accurately reach the water close to the near side of the high-speed large roll 43. The water agitation produced by the roll 43 not only ensures the presence of cold water at the point where the blanks 105 enter it, but also effects the existence of a constant current of water in a direction tending to carry the blanks well below the surface of the water.

The blanks, such as indicated at *a a*, then 115 pass under a series of immersed rolls 47 preferably idly mounted, suitable guiding tapes 48 being also preferably employed, but only below the rolls 47. Said rolls 47 can leave no marks upon the blanks such as are 120 usually left by tapes, and the tapes 48 leave no readily perceptible marks because the surfaces of the films of wax on the blanks are so instantly set or congealed when they first strike or enter the agitated current of 125 water near the roll 43 that the high finish or gloss of said surfaces is not noticeably affected by contact with the guiding tapes. The rolls 47 above the tapes can leave no marks at all. The latter are employed 130

chiefly to ensure retention of the blanks below the surface of the water long enough to fully congeal the films of wax throughout their slight thickness.

5 The tapes are mounted at one end on a roll 49 and their lower stretches pass under a roll 50 and a tightener roll 51 carried by arms 52 mounted in the tank. The other ends of the tapes are mounted on a roll 53 above which is a roll 54. From the tapes and the roll 54 the blanks pass between rolls 55, 56, which deliver them on a receiving belt 57 mounted on rolls at the ends of frame bars 58 supported by legs or standards 59.

15 The agitating and blank-deflecting roll 43 may be driven at the requisite relatively high speed in any suitable manner. For instance, as shown in Figure 1, a belt 60 may drive it from the roll 54. Said belt does not appear 20 in Figure 2 because of the line of section on which the latter is drawn.

For some purposes, as will presently be explained, all of the rolls above the wax basin will be covered with felt or cheese cloth as indicated in Figure 3, in order to carry 25 more wax on their peripheries than could be carried by uncovered metal. In said Figure 3 I illustrate how the cloth is mounted on roll 32, it being understood that all the other 30 rolls, when cloth covered, will have such cloth similarly mounted. The roll is formed with a groove or recess 61 extending its entire length. One edge of a piece of material 62, such as felt or cheese cloth or other 35 suitable material, is laid in the groove and gripped there by a key strip 63 secured by suitable means such as screws. After so securing one edge, the cloth is wrapped snugly around the roll at least once and a little more so that its other edge extends over and beyond the key strip. When first applied, 40 the free edge of the cloth can be made to adhere by the application of a little melted wax. Afterwards, the wax accumulated by 45 the rotation of the roll holds the free edge in place. The direction of wrapping is such, relatively to the direction in which the roll rotates, that in operation there is no tendency of the free edge to curl or roll up. In 50 other words the free edge extends in a direction opposite to the direction of rotation. When the machine is in operation, the rotation tends to keep the cloth snugly fitted to the roll and free from wrinkles.

55 If the rolls 31, 32, which are referred to as squeeze rolls because they squeeze off the surplus wax which has been poured or flooded onto the blanks in excess quantity, are unprovided with cloth coverings, or if coverings which were on them are removed, the 60 result will not be to produce finished blanks with glossy surfaces because said rolls then squeeze off too much wax to eventually exhibit a fine reflecting surface. If coated 65 blanks are desired with dull surfaces, the

rolls 31, 32, will have their cloth coverings removed. When both of the rolls 31, 32, are cloth covered, the coated blanks produced, issuing from the water bath, will have very 70 glossy surfaces. By removing one of such coverings, the resulting coated blanks will be highly glossed on one surface and dull on the other. This is illustrated by a comparison of Figures 4 and 5, the shaded surface indicating the glossy side of the blank 75 and the unshaded surface representing a dull or non-reflecting surface. There is a material advantage in this because there is little or no demand for boxes having glossy inner walls. Since the production of a glossy surface requires the use of more wax than for a dull surface, the lesser amount of wax 80 required to waterproof the surfaces of the blanks which are to be inside the boxes when made up, means considerable saving. I believe I am the first to produce blanks for paper boxes which, although both the inside and the outside of each box is coated, only the outside, which shows on the set up box, 85 is glossy.

The outside surface may be caused, by reflection therefrom, to exhibit a pattern. This is obtained by employing suitable cloth (cheese cloth for instance) for the covering of one of the squeeze rolls. The blanks pass 90 so quickly from the squeeze rolls into cold water that surface lines formed in the coating by said cloth do not have time to smooth out before being rendered permanent by the congealing effect of the water.

The result of directly flooding the blanks instead of dipping or immersing them or depending upon the action of rolls which deliver gaged films of wax to blanks passing between such rolls, is that said blanks do not 100 get heated to the inside or core, and the quick removal of the surplus wax and sudden immersion in cold water renders it impossible for the wax to more than merely adhere to the surfaces of the paper stock. 105 The blanks are not soaked in wax as when immersed, nor is the wax driven in by the pressure of any wax-applying rolls. I am therefore able to obtain moisture-proof blanks carrying the minimum amount of 110 wax and with no dark (soaked) spots, and having one or both surfaces very glossy.

In operation both surfaces of the blanks are practically deluged or flooded with wax in free motion because the wax reaches the 115 blanks in excess quantity when it strikes said surfaces. This avoids the soaking results of paper being dipped or immersed in hot wax or having the wax pressed into it by rolls. The surplus is removed evenly by the 120 rolls 31, 32, and the blanks are then successively plunged into a body of water which can never become lukewarm because of the current produced by the roll 43 at the point 125 where the blanks enter it, which current, at 130

the same time, aids in directing the blanks into a path which causes them to remain under water long enough to solidify the films of wax.

5. A new function or result accomplished by the employment of a plurality of pairs of rolls, and supplying the blanks with an excess of melted wax, instead of employing a single pair of rolls which themselves not only feed the blanks but also carry all the wax which ever reached the blanks, is that the said plurality of rolls suffice to cause the blanks to travel without subjecting them to pressure tending to force the wax below the surfaces of the blanks.

Having now described my invention, I claim:

1. The method of producing moisture-proof paper, consisting in flooding the paper with an indeterminate quantity of melted wax in free motion, without subjecting the paper to immersion in the wax, removing surplus wax from both surfaces of the paper, and cooling the wax before it is absorbed by the paper.

2. The method of producing moisture-proof blanks; consisting in flooding the blanks with an indeterminate quantity of melted wax in free motion, without subjecting the paper to immersion in the wax, removing surplus wax, and then plunging the coated blanks into a body of agitated cool water.

3. The method of producing moisture-proof blanks having one surface more heavily coated than the other, consisting in flooding the blanks with an indeterminate quantity of melted wax in free motion, removing surplus wax while permitting more to remain on one surface than on the other, and then cooling the wax before it is absorbed by the blanks.

4. A machine for coating paper, comprising a plurality of pairs of rolls for advancing the paper, means for supplying all of said rolls with an excess of melted wax, the last pair of rolls being relatively positioned to remove surplus wax, and a water tank for

receiving the paper from the said last pair of rolls.

5. A machine for coating blanks, comprising a plurality of pairs of rolls, means for feeding blanks thereto, means for supplying all of said rolls with an excess of melted wax, the last pair of rolls being relatively positioned to remove surplus wax, and a water tank for receiving the blanks from said last pair of rolls.

6. A machine for coating blanks, comprising a wax basin, a plurality of pairs of rolls the lower ones of which are located to dip into said basin, means for flooding all of the upper rolls with melted wax, and a water tank in position to receive blanks from said rolls.

7. A machine for coating blanks, comprising a wax basin, a plurality of pairs of rolls the lower ones of which are located to dip into the basin, a system of perforated pipes above the upper rolls, a wax reservoir and means for heating it, and a pump having connections to draw melted wax from the reservoir and deliver it to said pipe system.

8. A machine for producing wax-coated box blanks having a thicker coating on one surface than the other, said machine including a pair of rolls one of said rolls having an absorbent surface and the other having a relatively non-absorbent surface, means for supplying said rolls with melted wax, and means for causing the blanks to pass between said rolls.

9. A machine for producing box blanks having one surface glossy and the other surface dull, said machine including a pair of rolls one of said rolls having an absorbent surface and the other having a relatively non-absorbent surface, means for supplying said rolls with melted wax, means for causing the blanks to pass between said rolls, and means for chilling the blanks issuing from between said rolls.

In testimony whereof I have affixed my signature.

ELIE W. LABOMBARDE.
